UNITED STATES PATENT OFFICE.

JOHN BYSTROM, OF CHICAGO, ILLINOIS, ASSIGNOR TO ERIK L. KRAG, OF CHICAGO,
ILLINOIS.

LOOSE-LEAF BINDER.

1,257,803.

Specification of Letters Patent. Patented Feb. 26, 1918.

Application filed May 5, 1916. Serial No. 95,583.

To all whom it may concern:

Be it known that I, JOHN BYSTROM, a citizen of the United States, residing at Chicago, in the county of Cook and State of Illinois, have invented certain new and useful Improvements in Loose-Leaf Binders, of which the following is a description, reference being had to the accompanying drawings, forming a part of this specification, 10 in which corresponding numerals of reference in the different figures indicate like parts.

The object of my invention is to provide a simple, cheap and effective loose-leaf binder which shall be so constructed as to enable loose leaves to be clasped or released by the binding elements by means of an actuating screw connected therewith. I accomplish said object in the manner and by 20 the means hereinafter more particularly described and definitely pointed out in the claims.

In the drawings

Figure 1, is an inner face view of the 25 frame portion or hinged clamping members, Fig. 2, is a section taken upon the line 2, Fig. 1, viewed in the direction of the arrow there shown, the cover and supplemental back member being shown connected there- 30 with.

Fig. 3, is a section taken upon the line 3, Fig. 1, viewed in the direction of the arrow there shown, the cover portion being omitted, and

Fig. 4, is an enlarged section in detail, taken upon the line 4, Fig. 1, viewed in the direction of the arrow there shown.

Referring to the drawings, 1 indicates generally the main clamping frame consisting of counterpart clamping members having back portions 2 and 3 and clamping plates or flanges 4 and 5, bent in elbow form in cross section at a predetermined angle thereto, preferably less than a right angle, as clearly shown in Figs. 2 and 3. The parts 2 and 3 are hinged together throughout their length, as shown at 5^a. A supplemental back portion 6, formed from sheet metal, is provided with flanges 7, 7, the edges 45 of which are arranged to bear against the rear surfaces of the parts 2 and 3 respectively. Said parts 2 and 3 are provided with openings or perforations 8, Fig. 1, adapted to receive fingers or projections 9, 50 formed upon the edges of the flanges 7 for

the purpose of positioning or maintaining the supplemental back 6 in proper relation to the main or clamping frame 1. The parts 2 and 3 are cut away at 10, preferably midway between their ends, as shown in Figs. 1, 60 3 and 4, to receive a stirrup or screw receiving member 11 having parallel parts 12 bored to receive the hinge rods 13, Figs. 1 and 4, of the hinge which connects the parts 2 and 3, upon which rod said stirrup is 65 pivoted. The cross bar of said stirrup is bored in the plane of the bores of the members or arms 12 but at right angles thereto, which bore is threaded to receive an adjusting screw 14, having a head 15, swiveled in a bearing formed in a bearing-plate 16, attached by means of rivets 17, or otherwise to the part 6. Said swiveled head is provided with a socket 18, for the reception of a key 19, Fig. 4. An opening 20, in 70 the back 6, enables the key to be inserted within the socket. The frame members, together with the supplemental back are provided with a cover 21, Fig. 2, of any approved construction, which cover portion is 80 passed around the back and aids to secure the latter in place. Curved prongs 22, 23, are provided to serve as stops for the edges of the leaves 24, to be bound.

When the leaves are inserted with their 85 edges against the stops the screw 14 is turned so as to draw the stirrup or swiveled member toward the back 6. Each of the clamping members acts like an elbow lever with the edge of the flange 7 as its fulcrum, thereby causing the parts 4 and 5 to be forced toward each other and clamped upon the intervening leaves, while the hinge is drawn toward the rigid back member 6. In this 90 way any number of leaves from a comparatively few to as many as may be received between the parts 4 and 5, may be clamped. A reversal of the screw will serve to release 95 the leaves.

I do not wish to be limited to the construction shown, inasmuch as it may be varied without departing from the spirit of the invention.

Having thus described my invention, I claim:

1. A loose-leaf binder, comprising, in combination, clamping members elbow-shaped in cross section, said members having parallel clamping flanges and back portions, the latter being hinged to each other, a back 110

member spaced apart from said back portions with flanges arranged to bear against the rear outer portions of the latter, a screw threaded member jointedly attached to said hinge and a screw swiveled in said back member and in operative engagement with said screw threaded member for actuating said clamping members.

5 2. A loose-leaf binder having clamping members for holding leaves between them, said members being bent to form back portions hinged together upon a longitudinal axis, a supplemental back member having forwardly extended flanges arranged to

bear against the back portions of said clamping members in planes upon opposite sides of and parallel to said hinge and a swiveled screw for connecting said supplemental back member with said hinge to move the latter toward and from said back member.

15 20 In testimony whereof, I have signed this specification, in the presence of two subscribing witnesses, this third day of May, 1916.

JOHN BYSTROM.
